UNITED STATES PATENT OFFICE.

FRED LEE COLLINS, OF PUEBLO, COLORADO.

BRAKE LOCK.

Application filed March 15, 1927. Serial No. 175,574.

This invention relates to a lock designed for use in connection with air brakes or hand brakes of railway cars, one of the objects being to provide simple and efficient means whereby a brake, after being applied, will be held against release due to breakage of parts, leakage of air, etc.

A further object is to provide a device of this character which can be applied to a structure already in use and has means whereby the same can be disengaged readily from the restrained structure when release of the brake is desired.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is a side elevation of a portion of a car and brake structure thereon showing the present improvements combined therewith.

Figure 2 is a plan view of the mechanism shown in Figure 1, the operating rod being shown in section.

Figure 3 is an elevation of the combined rack guide and clamp.

Referring to the figures by characters of reference A designates a portion of a cylinder of the air brake apparatus of a car, the piston rod B being connected at C to a lever D forming a part of the brake mechanism.

The structure constituting the present invention includes a clamp 1 in the form of a split ring adapted to be placed around and to bind upon one end portion of the cylinder A, this clamp being provided with an extension 2 grooved as at 3 and provided with a cover plate 4 whereby the grooved portion and the plate will constitute a guide for a rack bar 5. This rack bar is slidably mounted and has ratchet teeth 6 along one face, there being a wing 7 at one end of the rack bar connected to the piston rod B at C.

Extending transversely of the cylinder A is a shaft 8 mounted for rotation in suitable bearings 9, there being a crank arm 10 at each end of the shaft adapted to be sup-

ported adjacent the side of the car E so that, if desired, the shaft can be rotated by hand by a person standing adjacent one side thereof. A crank 11 is provided on the shaft and is connected by a rod 12 to a bell crank 13. An actuating rod 14 is attached to the bell crank and is slidable within a guide 15 on the upper portion of the car E at one end thereof. This rod 14 has a handle or grip 17 by means of which it can be readily pushed and pulled. The collar 18 is secured to the rod 14 and a spring 19 is secured at its ends to this collar and to the guide 15 so as to hold the rod yieldingly in normal position. From this position the rod can either be thrust downwardly or pulled upwardly against the action of the spring 19.

Additional cranks 20 and 21 are extended from the shaft 8. Pivotedly mounted on the crank 20 is a bracket 22 provided with superposed guides 23 and 24 in which a pin 25 is slidably mounted. This pin has an eye 26 at its upper end and mounted on the pin is a spring 27 which thrusts against the guide 24 and against a collar 28 or the like carried by the pin so that the eye 26 is thus held normally pressed against the guide 24. A pawl 29 is pivotally mounted between ears 30 extending downwardly from the guide extension 2 and this pawl has a tail piece 31 extending loosely through the eye 26. The head of the pawl is heavier than the tail portion so that under normal conditions this head will gravitate away from the ratchet teeth 6.

A spring 32 is connected to the crank 21 and to the car structure and serves to exert a constant pull on said crank so as to hold it either raised or lowered when moved past the dead center. When the crank 21 is inclined downwardly and held by the spring 32 as shown in Figure 1 the guide 24 thrusts downwardly against spring 27 which, in turn, thrusts through collar 28 on the pin 25, thereby causing the eye 26 to pull downwardly on the tail 31 of the pawl. Thus the head of the pawl is pressed yieldingly into contact with the toothed portion 6 of the rack 5. When the brakes are applied the piston rod B will be projected outwardly relative to the cylinder A and as the rack bar 5 is connected to the piston rod, it will likewise move relative to the cylinder so that certain of the teeth 6 will slip over the pawl 29. Thus the pawl, cooperating with

the ratchet teeth will hold the rack and the piston against retrograde movement and will keep the brakes applied even though air should leak from the cylinder. Should it be desired to release the brakes the operator thrusts downwardly on the rod 14 so that the crank 11 is thus pushed backwardly away from the bell crank 13 and crank 21 is moved upwardly past its dead center 10 where it will be held by the spring 32. This rotation of shaft 8 will result in the crank 20 thrusting the bracket 22 upwardly. Consequently the eye 26 will be raised and push against the tail 31 of the pawl, forcing the head of the pawl out of engagement with the ratchet tooth. Obviously this actuation of shaft 8 could be effected, if desired, by rotating one of the cranks 10. After the brake has been released the parts can be reset by 20 pulling the rod 14 upwardly so as to move the crank 21 downwardly past its dead center, pull the pin 25 downwardly and elevate the head of the pawl where it will properly engage the ratchet teeth. As before stated springs 32 will hold the shaft 8 in either of the two positions to which it might be moved.

It is to be understood that the structure constituting this invention can not only be 30 attached to the cylinder as illustrated but can be bolted or otherwise attached to the car at any desired point. Furthermore the teeth of the rack can be so formed as to fit the ratchet brakes already in use, it merely

being necessary to make a slight change in 35 location which will be obvious to those skilled in the art.

What is claimed is:

1. The combination with brake operating mechanism including a lever and means for actuating the lever to apply the brake, of a bar movable with the lever and having ratchet teeth, a pawl, a bracket, yieldable means carried thereby engaging the pawl for holding it in or out of engagement with the ratchet teeth, means under the control of an operator for shifting the bracket in either of two directions, and yielding means for holding the bracket in either position to which it may be shifted. 40

2. The combination with brake mechanism including a lever and means for actuating the lever, of a bar movable with the lever and having ratchet teeth, a pawl, a guide for the bar, a rotatable shaft, means under the control of an operator for rotating the shaft, yielding means for holding the shaft in each of two extreme positions to which it may be rotated in either direction, a crank on the shaft, a bracket mounted thereon and adapted to be raised and lowered thereby during the back and forth rotation of the shaft, and yielding means carried by the bracket for shifting the pawl into and out of engagement with the ratchet teeth. 45

In testimony that I claim the foregoing as my own, I have hereto affixed my signature. 55

FRED LEE COLLINS.
